T. M. HOUSE

By Watson E. Coleman

Attorney

UNITED STATES PATENT OFFICE.

THOMAS M. HOUSE, OF RICHMOND, VIRGINIA, ASSIGNOR TO SEWARD TRUNK AND BAG COMPANY, OF PETERSBURG, VIRGINIA, A CORPORATION OF VIRGINIA.

DRAWER-LOCK.

1,312,032.

Specification of Letters Patent.

Patented Aug. 5, 1919.

Application filed September 19, 1917. Serial No. 192,152.

To all whom it may concern:

Be it known that I, THOMAS M. HOUSE, a citizen of the United States, residing at Richmond, in the county of Henrico and State of Virginia, have invented certain new and useful Improvements in Drawer-Locks, of which the following is a specification, reference being had to the accompanying drawings.

10 This invention relates to an improved drawer lock and more particularly to a simple and effective device for locking a series of drawers in a wardrobe trunk.

15 It is the primary object of my invention to provide means mounted upon the rear wall of the trunk section which is automatically actuated when one of the drawers is inserted into the trunk and caused to co-act with means on the remaining drawers to 20 securely lock the latter within the trunk section.

25 It is another and more particular object of the invention to provide a rectilinearly movable locking bar mounted upon the rear wall of the trunk section, drawer actuated means operatively connected to said bar and including means for imparting a vertical and lateral movement to the bar, and keeper elements on the rear walls of the drawers for 30 locking engagement by said bar.

35 It is also another object of my invention to provide a trunk drawer lock as above characterized, the several co-operating elements of which are so mounted and arranged that the 5 possibility of cutting or otherwise marring the lining of the trunk walls in the operative movement of the parts is precluded.

40 And it is a further general object of my invention to provide a drawer locking device for wardrobe trunks which is highly serviceable and convenient in practical use, consists of relatively few parts of simple form and which, therefore, may be manufactured and applied to trunks of the type referred to without materially increasing the cost of production.

With the above and other objects in view, my invention consists in the novel features of construction, combination, and arrangement of parts to be hereinafter more fully described, claimed, and illustrated in the accompanying drawings, in which,

Figure 1 is a front elevation of one section of a wardrobe trunk, several of the drawers being removed;

Fig. 2 is a vertical section taken on the line 2—2 of Fig. 1;

Fig. 3 is a similar view showing all of the drawers locked within the trunk section;

Fig. 4 is a detail horizontal section taken on the line 4—4 of Fig. 2;

Fig. 5 is a horizontal section taken on the line 5—5 of Fig. 3;

Fig. 6 is a detail perspective view showing certain of the operating parts for the locking bar;

Fig. 7 is a fragmentary perspective view illustrating the manner of engagement of the locking bar with the keeper on certain of the drawers; and

Fig. 8 is a similar view showing a slightly different form of the keeper member used upon the invertible trunk drawer.

Referring in detail to the drawings, 5 designates one section of a wardrobe trunk which may be constructed in any ordinary or approved form but, as shown, is provided upon the inner faces of its side walls with the angular metal drawer supporting strips 6. Preferably, though not necessarily, one 80 or more horizontal boards or walls indicated at 7, is riveted or otherwise secured upon the corresponding metal strips 6 intermediate of the ends of the vertical trunk walls to brace and strengthen the walls 85 against external pressures.

The several drawers indicated generally by the numeral 8, may be of any desired depth, said drawers as well as the walls of the trunk section being covered with a suitable dining material. The upper drawer 8 is provided in the upper edge of its front

of the V-shaped lever. In this normal position of the locking bar, the link 23 extends downwardly and rearwardly at an inclination, as clearly seen in Fig. 2 of the drawings. 70

As hereinbefore stated, it is the purpose of the present invention to provide means which, when the top drawer is moved into the trunk section into position to be locked, will automatically co-act with means on each of the other drawers and simultaneously lock the latter in the trunk section. To this end, I have illustrated in the accompanying drawings what I have found to be a very simple and practical embodiment of the invention. This locking means includes a metal bar 11 which is movable in spaced relation to the rear wall of the trunk over the spaced wear plates 12. The terminals of a metal guide strip 13 which extends over the bar 11 are riveted, together with the ends of the plate 12, to the trunk wall. 75

To the rear wall of the trunk adjacent the top thereof, a metal plate 14 is suitably secured, and to this plate the longer arm 15 of a substantially V-shaped lever is pivotally connected at its end as indicated at 16. The relatively short arm 17 of said lever terminates in an angularly disposed flange 18 in which a slot 19 is provided. The upper end of the locking bar 11 is pivotally connected to said lever at the juncture point of the arms 15 and 17, as shown at 20. 80

To the under side of the top wall of the trunk section, a metal plate 21 is securely riveted, said plate being angularly bent adjacent one of its ends away from the trunk wall and terminating in a relatively narrow, upwardly projecting, angular lug 22. A rigid metal link 23 has a slot 24 in one of its ends, through which the lug 22 is loosely engaged. In spaced relation to its other end, said metal link is angularly bent as shown at 25 and said latter end of the link likewise terminates in a relatively narrow, angularly bent lug 26 which extends upwardly through the slot 19 in the flange 18 on the lever arm 17 and has loose engagement therein. 85

A metal wear plate 27 is also secured to the rear wall of the trunk section adjacent its lower end and, to this place, one end of a lever 28 is pivoted, as at 29, the other end of said lever being pivotally connected, as at 30, to the lower end of the locking bar 11. 90

The upper end of a coil spring 31 is attached to the lower end of the arm 15 of the V-shaped lever, the lower end of said spring being secured by the fastening rivet for the uppermost wear plate 12. This spring, by its contractile action, normally urges the locking bar 11 downwardly so that the lower end thereof engages the bottom wall of the trunk, the lever 28 being disposed substantially at the same inclination as the arm 15 95

The two lower drawers are relatively large and the second drawer from the bottom has a hinged rear wall 32 which is held in a vertical position by a spring latch plate 33 or in a folded position upon the bottom wall of said drawer by the spring plate 34. When the wall 32 of the drawer is folded inwardly and downwardly on the bottom wall, said drawer may be inserted into the trunk section in an inverted position when a large hat or other article is contained within the lowermost drawer. To the rear edge of the bottom wall of this invertible drawer, a keeper plate 35 of the form shown in Fig. 8 of the drawings, is secured, said plate having angularly bent portions terminating in oppositely extending keeper lugs 36. To the rear vertical wall of each of the other drawers with the exception of the top drawer, a keeper member 37, such as shown in Fig. 7 of the drawings, is secured, said member consisting simply of a metal strip fixed at one end to the drawer wall and having its other end angularly offset and spaced from said wall. By the provision of the keeper 35 for the invertible drawer as shown, the locking bar will operatively engage one or the other of the terminal lugs 36 of said keeper in either position of the drawer. 100

To the rear wall of the trunk section, in spaced relation to each of its side walls, a vertical stop cleat 38 is secured. These stop cleats limit the inward movement of the drawers so that they will not engage with the locking bar 11 or the levers connected to the ends thereof. 105

The relatively narrow top drawer has a wear plate 39 centrally secured upon the upper edge of its rear wall, as seen in Fig. 3, said plate being bent centrally and the ends thereof extending downwardly upon the inner and outer faces of the drawer wall and securely riveted or otherwise fixed thereto. 110

Having above described the several features of my improved drawer locking device, its operation will be readily understood. All of the drawers with the exception of the top drawer, having been inserted into the trunk, said drawers may be simultaneously locked and held against outward movement simply by the insertion of the top drawer. When this latter drawer is inserted, the wear plate 39 will engage the downwardly inclined link 23 and force said link upwardly toward the top wall of the trunk. In the upward movement of the rear end of this link, the V-shaped lever is swung upwardly and, owing to the angular relation of the pivoted arm 15 of this lever with 115

respect to the locking bar, it is manifest that the bar 11 will be moved upwardly against the action of the spring 31 and, at the same time, moved laterally in its guides toward the right and into co-acting engagement with the keeper elements on the several drawers. By angularly bending the link 23 downwardly at its rear end, the possibility of the flanged end of the lever arm 17 and the connected end of the link 23 being forcibly engaged with the top wall of the trunk and distorted or in any way injured so that the proper operation of the device might be interfered with, is entirely obviated. When the top drawer 8 has been fully inserted and the other drawers locked as just explained, the lock 9 is operated by means of a key and the lock bolt engaged in the keeper 10. Thus, all of the drawers are securely locked in the trunk section from a standing position, and the inconvenience and physical discomfort incident to the operation of individual locks for the several drawers is avoided. It is also apparent that by the elimination of such separate locks, the manufacturing cost of the trunk may also be appreciably reduced. By means of the present invention, the series of drawers may be securely locked in the trunk section in an expeditious manner and with a minimum of manual exertion, so that the user will be assured of the security of the contents of said drawers when the trunk is left open or the sections thereof separated.

I have above referred to the particular mounting and arrangement of the locking bar upon the trunk wall, but it is to be understood that such mounting is susceptible of many mechanical variations and may be embodied in numerous alternative forms. Therefore, while I have herein shown and described what I at present believe to be the best embodiment of the invention, it is to be understood that I expressly reserve the privilege of adopting all such legitimate modifications of which the invention is susceptible as may be fairly embodied within the spirit and scope of the invention as claimed.

Having thus fully described my invention, what I desire to claim and secure by Letters Patent is:

1. The combination with a structure having a plurality of removable drawers, of locking means for said drawers including a movable locking member, a rigid element mounted at one of its ends upon one wall of said structure and operatively connected at a point intermediate of its ends to said locking member, means on the drawers for operative engagement by said locking member, and drawer actuated means coacting with the other end of said element to move said member to its effective locking position upon the insertion of the drawer.

2. The combination with a structure having a plurality of removable drawers, of a locking member mounted upon one wall of the structure, a rigid element mounted at one of its ends upon said wall and operatively connected intermediate of its ends to the locking member, means secured to the rear walls of said drawers for engagement by the locking member, and drawer actuated means coacting with said element to move said member to its effective locking position upon the insertion of the drawer.

3. The combination with a trunk section having a plurality of removable drawers, of a vertically and laterally movable bar mounted upon the rear wall of said trunk section, a lever operatively connected to the upper end of said bar and having diverging arms, one of which is pivotally mounted upon the trunk wall, means mounted upon the under side of the top wall of the trunk and connected to the other lever arm adapted to be operatively engaged by the top drawer when the latter is inserted to move the bar to locking position, and means on the remaining drawers with which said bar co-acts to lock the latter drawers within the trunk section.

4. The combination with a trunk section having a plurality of removable drawers, of a locking member movably mounted upon the rear wall of the trunk section, an element pivotally mounted at one of its ends upon said trunk wall and operatively connected at a point intermediate of its ends to the locking member, means secured to the rear walls of the drawers for engagement by the locking member, and drawer actuated means coacting with said pivoted element upon the insertion of a drawer to move said member to its effective locking position.

5. The combination with a trunk section having a plurality of removable drawers, of a vertically and laterally movable locking bar mounted upon the rear wall of said trunk section, a lever operatively connected to said locking bar and having diverging arms, one of which is pivotally mounted on the trunk wall, a link loosely connected at one of its ends to the under side of the top wall of the trunk and operatively connected at its other end to the other arm of said lever, said link being engaged by the top drawer when inserted into the trunk section to actuate said lever and move the bar to locking position, and keeper elements on the remaining drawers for engagement by said bar to lock the latter drawers within the trunk section.

6. The combination with a trunk section having a plurality of removable drawers, of a vertically and laterally movable locking bar mounted upon the rear wall of the trunk section, a lever having diverging arms, one of which is pivotally mounted upon the rear

4
wall of the trunk, said locking bar being pivotally connected to said lever at the juncture of the arms, the other of said lever arms having an angularly disposed terminal 5 flange, a plate movably supported at one end upon the under side of the top wall of the trunk and loosely connected at its other end to the flange of said lever arm, said plate being engaged by the top drawer when the 10 latter is inserted to actuate the lever and move the bar to locking position, and keeper elements on the remaining drawers with which said bar co-acts to simultaneously lock the latter drawers within the trunk section.

15 7. The combination with a trunk section having a plurality of removable drawers, of a movable locking bar mounted upon the rear wall of the trunk section, a lever pivotally mounted at one of its ends upon the 20 trunk wall and operatively connected at a point intermediate of its ends to the upper end of the locking bar, means secured to the rear walls of the drawers for engagement by the locking bar, and drawer actuated means 25 mounted on the top wall of the trunk section and coacting with said pivoted lever upon the insertion of a drawer to move the locking bar to its effective locking position.

8. The combination with a trunk section 30 having a plurality of removable drawers, of a movable locking bar mounted upon the rear wall of the trunk section, a lever pivotally mounted at one of its ends upon said rear wall and adjacent to the top wall of 35 the trunk section, said lever being operatively connected to the locking bar, means on the rear walls of the drawers for engagement by the locking bar, and drawer actuated means mounted on the top wall of the 40 trunk section and coacting with the other end of said lever upon the insertion of the drawer to move said bar to its effective locking position.

9. The combination with a trunk section 45 having a plurality of removable drawers, of a laterally movable bar mounted upon the rear wall of the trunk, a plate loosely mounted at one of its ends upon the under side of the top wall of the trunk, a movable 50 element mounted upon the rear wall of the trunk and connected to the upper end of the locking bar, the other end of said plate being directly engaged with said element, said plate being engaged and actuated by the top 55 drawer when inserted to move the bar to its locking position, and keeper elements on the remaining drawers with which said bar co-acts to simultaneously lock the latter drawers within the trunk section.

60 10. The combination with a trunk section having a plurality of removable drawers, of a laterally movable locking bar mounted upon the rear wall of said trunk section, a lever pivotally mounted 65 upon the rear wall of the trunk for move-

ment in a plane parallel thereto and pivotally connected to the upper end of the locking bar, said lever having an angularly disposed arm, means mounted upon the under side of the top wall of the trunk operatively 70 connected to said lever arm and engaged by the top drawer when inserted into the trunk section to move the bar to its locking position, and keeper elements on the remaining drawers with which said bar co-acts to lock 75 the latter drawers within the trunk section.

11. The combination with a trunk section having a plurality of removable drawers, of a vertically movable locking bar mounted upon the rear wall of said trunk section, a 80 lever mounted at one of its ends upon said trunk wall and above and at one side of the locking bar, the other end of the lever extending beyond the relatively opposite side of the locking bar, said bar at its upper end 85 being operatively connected to the lever, means on the drawers for engagement by the locking bar, and drawer actuated means co-acting with the latter end of the lever upon the insertion of a drawer to move the bar to 90 its effective locking position.

12. The combination with a trunk section having a plurality of removable drawers, of a vertically and laterally movable locking bar mounted upon the rear wall of said 95 trunk section, levers pivotally mounted upon the rear wall of the trunk, said levers being pivotally connected respectively to the upper and lower ends of the bar, said upper lever having an angularly disposed arm, 100 means movably mounted upon the under side of the top wall of the trunk section and operatively connected to said arm, the top drawer when inserted actuating said means to move the bar to its locking position, 105 keeper elements on the remaining drawers with which said bar co-acts to simultaneously lock the latter drawers within the trunk section, and a lock for the top drawer.

13. The combination with a trunk section 110 having a plurality of removable drawers, of a movable locking bar mounted upon the rear wall of said trunk section, levers movably mounted upon said trunk wall and operatively connected respectively to the 115 upper and lower ends of said bar, the upper lever being provided with an arm extending at an angle with respect to the locking bar, means on the rear walls of the drawers for engagement by said bar, and drawer actuated means to coact with the arm of said upper lever upon the insertion of a drawer and move the bar to its effective locking position.

14. The combination with a trunk section 125 having a plurality of removable drawers, of a movable locking bar mounted upon the rear wall of said trunk section, levers movably mounted upon said trunk wall and operatively connected respectively to the 130

upper and lower ends of said bar, the upper lever being provided with an arm extending above the upper end of the locking bar, means on the rear walls of the drawers for engagement by said bar, and drawer actuated means mounted upon the top wall of the trunk section to coact with the arm of said upper lever upon the insertion of a

drawer and move the bar to its effective locking position.

In testimony whereof I hereunto affix my signature in the presence of two witnesses.

THOMAS M. HOUSE.
